DESIGN FOR A BRUSH OR THE LIKE

Melvin H. Partridge, New Rochelle, N. Y., and
Frederick W. Weitzel, Frederick, Md., assignors to Ox Fibre Brush Company, Inc., New York,
N. Y., a corporation of Delaware

Application June 9, 1938, Serial No. 77,688

Term of patent 14 years

To all whom it may concern:

Be it known that we, Melvin H. Partridge and Frederick W. Weitzel, both citizens of the United States, residing respectively at New Rochelle, in the county of Westchester and State of New York, and Frederick, in the county of Frederick and State of Maryland, have invented a new, original, and ornamental Design for a Brush or the Like, of which the following is a specification, reference being had to the accompanying drawing, forming part thereof.

Figure 1 is a side elevation of a brush or the like showing our new design, and Fig. 2 is a plan of the same.

We claim—

The ornamental design for a brush or the like, substantially as shown.

MELVIN H. PARTRIDGE.
FREDERICK W. WEITZEL.
